(57) **CLAIM**

The ornamental design for a fat screw press as shown and described.

DESCRIPTION

FIG. 1 is the perspective view of the fat screw press;

FIG. 2 is the front view thereof;

FIG. 3 is the rear view thereof;

FIG. 4 is the left side view thereof;

FIG. 5 is the right side view thereof;

FIG. 6 is the top plan view thereof; and,

FIG. 7 is the bottom plan view thereof.

The broken lines in the drawings are for the purpose of illustrating portions of the fat screw press that form no part of the claimed design.

1 Claim, 7 Drawing Sheets
